(57) **CLAIM**

I claim the ornamental design for a hour symbol for a watch face, as shown and described.

DESCRIPTION

FIG. 1 is a bottom side plan view of a design for the hour symbol for a watch face;

FIG. 2 is front side view of the claimed design;

FIG. 3 is left side view thereof;

FIG. 4 is right side plan view thereof;

FIG. 5 is top plan view thereof;

FIG. 6 is a rear plan view thereof;

FIG. 7 is a perspective view showing the front side, left side and top side thereof; and,

FIG. 8 is perspective view of the hour symbol in its environment on a watch face.

The broken line showings of FIGS. 2-4, FIG. 6 and FIG. 8 are environmental only and form no part of the claimed design.
